TOOTH BRUSH

David M. Coney and Zachary T. Coney, San Francisco, Calif.

Application May 27, 1936, Serial No. 82,072

4 Claims. (Cl. 15—188)

This invention relates to a toothbrush of the type disclosed in our former Patent Number 1,924,152, entitled "Toothbrush"; that is, a brush composed of one or more inner rows of hog's hair bristles and a pair of exterior rows of rubber bristles, and especially to an improved method and structure for securing the rubber bristles in the head of the brush.

The object of the present invention is generally to improve and simplify the construction and operation of brushes of the character described, and especially to provide a rubber bristle which is constructed in strip form, together with means for securing, anchoring, or fastening the strip in the head of a brush.

The invention is shown by way of illustration in the accompanying drawing, in which—

Fig. 1 is a perspective view of the head and a portion of the handle of the toothbrush, said view showing the rubber bristles removed and also showing the grooves in which the rubber bristles are inserted;

Fig. 2 is a cross section taken on line II—II of Fig. 1;

Fig. 3 is a similar section showing the rubber bristles in place;

Fig. 4 is a perspective view showing the strip form of the rubber bristles;

Fig. 5 is a perspective view of the anchor member;

Fig. 6 is a plan section taken on line VI—VI of Fig. 4; and

Fig. 7 is a perspective view showing a modified form of the anchor strip.

Referring to the drawing in detail, and particularly Figs. 1 and 3, A indicates the handle and B the head of a toothbrush. Suitably secured in the head are two or more rows of hog's hair bristles C, and arranged exteriorly thereof and 40 parallel thereto are two rows of rubber bristles D, one on each side.

This general arrangement of hair and rubber bristles is old, as it is disclosed in our former Patent Number 1,924,152, but the construction 45 and method of anchoring the rubber bristles is new and forms the subject matter of the present application.

In molding, pressing, or otherwise forming the handle and the head of the brush, which is made 50 from celluloid, or a similar material, two longitudinally extending grooves 2—2 are formed, one on each side of the head. These grooves are provided for the reception of rubber strips 3—3, on which are formed integral rubber bristles 4. 55 The strips carrying the rubber bristles 4 may be

molded, punched, cut, or otherwise formed from rubber and have a groove 5 formed on the inner face thereof, said groove extending substantially from end to end of the strip and terminating in holes 6 at each end, said holes extending completely through the strip. The groove 5 and the holes in which it terminates are provided for the reception of an anchor member made of celluloid. This anchor member is best shown in Fig. 5 and consists of a bar 7 having a pin 8 formed at 10 each end thereof.

In actual practice it was found that cement, such as is employed in conjunction with celluloid, was not suitable for rubber. At least, such cement would not adhere to the rubber with sufficient strength to prevent the rubber strips from gradually working out of the grooves. This defect has been entirely overcome in the present instance.

The anchor member employed is formed of 20 celluloid; consequently when the celluloid cement is applied, the anchor strip will become bonded to the celluloid material forming the head of the brush. This is accomplished as follows: The anchor strip is first inserted in the groove 5 of 25 the rubber strip. Cement is then applied to the outer face 9 of the celluloid anchor strip, and also to the ends indicated at 8. Cement is also placed in the groove 2. The rubber strip, together with the anchor bar placed therein is then inserted in 30 the groove 2, and when inserted, a cement bond will be formed between the faces of the groove 5 and the anchor strip. In this manner, the rubber strip is securely anchored, as the anchor strip which is cemented in the groove of the head 35 extends into the groove 5 of the rubber strip, and also completely through it.

While the anchor member here shown is only provided with two pins, such as indicated at 8, a center pin may be added as indicated at 10 in 40 Fig. 7, or any number of additional pins may be employed; and while these and other features of the invention have been more or less specifically described and illustrated, we wish it understood that various changes may be resorted to within 45 the scope of the appended claims. Similarly, that the materials and finish of the several parts employed may be such as the manufacturer may decide, or varying conditions or uses may demand.

Having thus described our invention, what we 50 claim and desire to secure by Letters Patent is:—

1. The combination with a head, said head having an elongated groove formed therein, of a rubber strip in the groove, said strip having projecting rubber bristles and said strip having a 55

groove formed in one side thereof and extending substantially from end to end of the strip, and an anchor bar in the strip groove and extending from end to end of the groove, said anchor bar engaging one side of the groove in the head and being cemented thereto to secure the rubber strip against removal.

2. The combination with a head, said head having an elongated groove formed therein, of a 10 rubber strip in the groove, said strip having projecting rubber bristles and said strip having a groove formed in one side thereof and extending substantially from end to end of the strip, an anchor bar in the strip groove and extending 15 from end to end of the groove, said anchor bar engaging one side of the groove in the head and being cemented thereto to secure the rubber strip against removal, and pins on the bar extending through the strip and engaging the opposite face 20 of the groove in the head and being cemented thereto.

3. A structure for securing a rubber strip having rubber bristles formed thereon comprising a head, said head being constructed of celluloid 25 and having an elongated groove formed therein,

a groove formed in one side of the rubber strip, and a celluloid bar in said last mentioned groove and extending from end to end thereof, said rubber strip, with the celluloid bar placed therein, being located in the groove of the head and said bar being cemented to one face of the groove in the head to anchor the rubber strip against removal.

4. A structure for securing a rubber strip having rubber bristles formed thereon comprising a head, said head being constructed of celluloid and having an elongated groove formed therein, a groove formed in one side of the rubber strip, a celluloid bar in said last mentioned groove and extending from end to end thereof, said rubber 10 strip, with the celluloid bar placed therein, being located in the groove of the head and said bar being cemented to one face of the groove in the head to anchor the rubber strip against removal, and members on the bar projecting completely 15 through openings formed in the rubber strip and being cemented to the opposite face of the groove.
